ROTATABLE WHEEL MARBLE RUNWAY GAME

Ernest J. Swimmer, 340 E. 52nd St., New York, N.Y.
10022, and Alan A. Hicks, Timothy Road, Weston,
Conn. 06880

Filed Aug. 6, 1969, Ser. No. 18,567

Term of patent 14 years

Int. Cl. D21—01

U.S. Cl. D34—15

FIG. 1, is a view in elevation showing one side face of the rotatable wheel marble runway game, and

FIG. 2, is a view of the face opposite that in FIG. 1.

FIG. 3 is an end view in elevation, both elevation end views being alike.

FIG. 4 is a top plan view.

We claim:

The ornamental design for rotatable wheel marble runway game, as shown and described.
